COMBINED TROPHY AND TROPHY SUPPORT

Dorothy K. Allen, Libertyville, Ill., assignor to F. H. Noble & Company, Chicago, Ill., a corporation of Illinois

Original design application Nov. 15, 1967, Ser. No. 9,427.
Divided and this application May 27, 1969, Ser. No. 18,540

Term of patent 14 years

Int. Cl. D11—02

U.S. Cl. D29—28

The dominant features of my design are shown in full lines.

FIG. 1 is a perspective view of a combined trophy and trophy support showing my new design.

FIG. 2 is a front elevational view thereof;

FIG. 3 is a side elevational view;

FIG. 4 is a top plan view; and

FIG. 5 is a bottom plan view.

This application is a division of design application Ser. No. D.9,427, filed Nov. 15, 1967.

I claim:

The ornamental design for a combined trophy and trophy support, substantially as shown and described.

No references cited.
